(No Model.)

J. F. THAYER.
BUTTON SETTING INSTRUMENT.

No. 459,480.

Patented Sept. 15, 1891.

WITNESSES,

INVENTOR

Charles Harrigan, James F. Thayer.
H. E. Carpenter by Remington & Huntington
Attns.

UNITED STATES PATENT OFFICE.

JAMES F. THAYER, OF PROVIDENCE, RHODE ISLAND.

BUTTON-SETTING INSTRUMENT.

SPECIFICATION forming part of Letters Patent No. 459,480, dated September 15, 1891.

Application filed December 6, 1890. Serial No. 373,818. (No model.)

To all whom it may concern:

Be it known that I, JAMES F. THAYER, a citizen of the United States, residing at Providence, in the county of Providence and State 5 of Rhode Island, have invented certain new and useful Improvements in Button-Setting Instruments; and I do hereby declare the following to be a full, clear, and exact description of the invention, such as will enable others 10 skilled in the art to which it appertains to make and use the same, reference being had to the accompanying drawings, and to letters of reference marked thereon, which form a part of this specification.

15 My invention has relation generally to instruments for attaching buttons to fabrics, &c., by means of metallic fasteners, but more particularly to the class of portable or hand-operated instruments provided with removable reservoirs or magazines containing the ready-threaded or combined buttons and two-prong fasteners, two jaw members arranged to be opened and closed, and mechanism for intermittently withdrawing a button and fastener from the reservoir and attaching it to the fabric or shoe by the action of said jaw members.

The button-setting instrument forming the subject of my present application for patent 30 consists, essentially, of a lower jaw or anvil, a fixed vertically-arranged holder or guide secured to and moving in unison with the lower jaw, adapted to receive threaded buttons and fasteners, a removable tube or magazine also 35 adapted to contain similar buttons and fasteners, communicating with said holder, yielding stops for arresting or supporting the column of buttons and fasteners and checking them singly from the bottom of the column, a pivotally-mounted upper jaw arranged and adapted to actuate said stops, and a driver secured to the free end of the movable jaw, all constructed and arranged whereby the act of opening the jaws in the 40 upstroke checks off and releases the lowest button and fastener from the lower end of the column, which immediately drops to the lower portion of the holder, so that the jaw in its return or down stroke engages the said 45 button and fastener and forces the prongs thereof through the leather or fabric and

against the anvil, thereby clinching the prongs and attaching the button.

In the accompanying sheet of drawings, Figure 1 is a side elevation of my improved 55 button-setting instrument, a button being shown in position to be attached to the fabric upon bringing the jaws together. Fig. 2 is a similar view showing the relation of the parts at the end of the attaching operation. 60 Fig. 3 is a partial front elevation of the holder, &c., the buttons being omitted. Fig. 4 is a longitudinal sectional view taken on line *v v* of Fig. 3, the relation of the parts in this and the preceding figure corresponding with that 65 shown in Fig. 1. Fig. 5 is a horizontal sectional view taken on line *xx* of Fig. 2. Fig. 6 is a longitudinal sectional view taken transversely through the center of the upper portion of the holder, &c., corresponding to Fig. 2. Fig. 70 7 is a side elevation of the upper portion of the holder and movable jaw, the latter being in the act of withdrawing the spring-stop from the lowest button and fastener. Fig. 8 is a horizontal sectional view taken on line *o o* of 75 Fig. 2. Fig. 9 is a top view of the tube or reservoir. Fig. 10 is a horizontal sectional view thereof taken on line *aa* of Fig. 1, and Fig. 11 is an end view of the upper jaw.

A more detailed description of the construction and manner of operation of my improved button-setting instrument is as follows:

The implement as a whole is designated by A.

The two handle members *a b* are provided 85 with jaws *a' b'*, respectively, jointed together at *p*, the lower handle having secured thereto a spring *s*, the free end of which bears against the upper member *a*. The outer or free end of the jaw *a'* constitutes an anvil, in which 90 is mounted the setting-die *a'*, arranged to bend and clinch the two prongs of the fasteners *f'*.

To one side of and parallel with the handle *a* is secured by screws *c* an arm *c*. The front 95 or free end is enlarged, and consists of two parts secured together by a screw *c*. (See Fig. 8.) To this enlarged end are fixed two longitudinally-grooved vertical sides *d*, whose upper ends *d'* are attached together at the 100 back. These sides, combined with a grooved piece *d* fitted therein, form a stationary guide

or runway and holder for the buttons n and threaded fasteners f' as they are intermittently dropped from the arrester m^2 , soon to be described.

5 The magazine or button and fastener holding tube t is removably secured to the upper portion of the stationary guide. The tube is provided at the back with a central longitudinal narrow groove r , a corresponding opening 10 r^2 being formed in the front of the tube. Said grooves are adapted to receive the eyes or shanks n^4 of the buttons, thereby also serving as a lateral guide. Side grooves r' are formed in the tube, along which the fasteners 15 freely travel. A spring-stop t^3 at the upper end of the tube prevents the buttons from dropping out.

The magazine t is fitted into a socket formed in the upper portion of the stationary guide 20 d , as stated, a spring m , secured to the latter, holding the tube in place. As shown, this spring extends downwardly through the enlargement d' and terminates in the outwardly-bent end m^2 , arranged to engage and arrest 25 the column of buttons and fasteners. (See Fig. 6.) Contiguous to this spring-stop is formed a lateral extension m' , the same being in engagement with a short arm e' of a latch e , pivoted to one side of the head d' .

30 From the foregoing it is apparent that upon forcing the stop m^2 rearwardly, or as shown in Fig. 4, the buttons and fasteners would instantly fall and fill the holder and clog it. In order to prevent such clogging of the holder, 35 I provide a yielding normally-stationary check h , having its upper portion h' extending across the front of the holder and at an angle thereto, its inner face being some distance above the stop m^2 and in engagement 40 with the lowest button of the column, thereby forming a separator. (See Figs. 1 and 4.) A pin i' , secured to the holder, limits the downward movement of the latch, and consequently limits the forward movement of 45 the spring-stop m^2 . The free end g^4 of the upper jaw member b' is reduced or made somewhat narrower than the body portion, (see Fig. 5 and also Figs. 1, 7, and 11,) in order that it may enter the rear space formed 50 by the lateral separation of the two sides d . The said end g^4 of the jaw is provided with a downwardly-extending driver or die g , having a vertical slot g^8 , Figs. 3 and 11, in its 55 lower end arranged to receive the button-eye n^4 edgewise, the adjacent ends of the die at the same time being beveled or adapted to engage the upper portion of the button-fastener f' , so that on applying sufficient pressure to the jaw the driver acts to force 60 the prongs of the fastener downwardly through the fabric or material f and clinch them thereunder, the setting-die a^2 at the same time deflecting the prongs laterally for that purpose. The jaw b' is further provided 65 with a pin i , arranged to engage an arm e^2 of the said latch e , thereby controlling the movement of the stop m^2 . The pin is further

adapted to engage the yielding check h for the purpose of regulating the movement of the separator h' , used for checking off the buttons. The relation of the pin i , &c., to the latch and check may be adjusted by means of a stop s' , attached to the handle a by a screw s^3 , passing through a slotted opening formed in the stop. (See dotted lines s^6 , Fig. 1.)

70 The operation of the implement A in use 75 may be described as follows: Assuming, first, that the fabric or leather f and the button n to be next attached thereto are in place, (see Figs. 1 and 4,) now upon vibrating the handle b in the arrow direction the result of such movement will be to force the jaw b' downwardly or in the downstroke, its first action 80 then being to withdraw the pin i from engagement with the latch e , the spring m immediately carrying the latter to its limit against the stop i' , thus placing the arrester or stop m^2 in position below and in line with the column of buttons and fasteners supported by the separator h' . The continued 85 movement of the jaw next brings the pin i into engagement with the yielding check h , resisted by the pin i' , and forces the separator away from the column of buttons, which then drops a short distance—equal, say, to the 90 diameter of a button—or until arrested by the stop m^2 , the final movement of the jaw in its 95 downstroke causing the driver g to engage the fastener and force the prongs thereof through the leather and clinching them, the die a^2 at 100 the same time assisting in the operation, the relation of the several parts then being substantially as represented by Figs. 2, 5, and 6. The jaw now in its upstroke, assisted by the 105 spring s , acts first to remove the pin i from the spring-check h , thus allowing the latter to automatically return to its normal position 110 against the pin i' , its upper end portion h' thereby passing over the lower button of the column (being the next to be attached) and into engagement with the adjacent button. (See Fig. 7.) The further and final movement 115 of the jaw upwardly vibrates the latch through the medium of the pin i , thereby withdrawing the arrester m^2 from the lower button and fastener, which immediately drop past the driver to the lower portion of the holder, as indicated by dotted lines in Fig. 4, ready to be attached upon repeating the operation before described.

120 I would add that the front opening r^5 and lateral grooves r' , formed in the lower portion of the holder, are made, preferably, somewhat narrower than the corresponding opening and grooves formed in the other portion of the 125 holder and magazine. This is done to prevent the fastener from dropping too far upon being released from the stop m^2 , as otherwise the projecting prongs of the fastener would seriously interfere with a withdrawal of the 130 work from the instrument. It will be seen by referring to Fig. 3 that the lower end of said opening r^5 is well rounded, as at g^2 , thus readily permitting the removal of the work at the

front after the button is attached to the fabric *f* and in advance of and preparatory to setting the succeeding button.

From the foregoing it is obvious that a button-attaching machine embodying my improvements is very simple in construction and manner of operation, the several parts coacting in a positive manner and producing practically perfect work, its capacity being limited only by the ability of the operator to manipulate it.

A number of the tubes or magazines are kept charged with threaded buttons and fasteners, ready to be substituted and attached singly to the instrument as fast as the empty ones are removed.

It will be seen that, although the handles or jaws are jointed together, really but one jaw or member *b* is practically movable to any extent, and this simply carries the driver *g* and a pin *i* or other equivalent means, which upon vibrating the jaw engages and controls the movement of the check-plate *h* and yielding arrester or stop *m*². The other jaw or member *a* is provided with a holder *d*, &c., to which the magazine, check-plate, latch, spring *m*, and its extensions *m'* *m*² are attached. By this arrangement, as before described, the work is withdrawn directly from the lower part at the front of the holder *d*, because the vertical space *a'*, Fig. 3, between the end of the holder and face of the anvil is too small or narrow to allow the work to be removed by withdrawing the attached button from the end of the holder. In this, as well as in some other respects, my invention differs from other button-attaching machines. The supplemental tube *d'*, fitted into the side grooves of the holder *d*, is practically a continuation of the tube *t*. (See Figs. 3, 4, and 5.) This is done because it is cheaper to thus make the holder than it would be to attempt to form the narrow grooves *r'* *r*² in the holder itself.

I claim as my invention—

1. A button-setting instrument having a pair of pivoted jaws, a holder or guide adapted to receive a column of threaded buttons and fasteners, the holder being arranged between the jaws and moving in unison with the lower jaw or anvil member, mechanism for intermittently checking a button and fastener from the column, and a driver secured to the upper jaw member, arranged to move between the two sides of said holder and engage the fastener, substantially as described.

2. In a button-setting instrument, the combination of a pair of pivoted jaw members, a holder or guide mounted between the jaws and arranged in a fixed position or relation to the lower jaw or anvil member, two yielding stops actuated and controlled by the movement of the opposite or upper jaw member for intermittently checking off a combined button and fastener from a string of buttons and fasteners mounted in said holder, and a driver secured to and moving in unison with the upper jaw, arranged to engage the fastener and attach it to the fabric or material introduced between the adjacent faces of the holder and setting-die, substantially as described.

3. In a button-setting instrument provided with upper and lower jaw members adapted and arranged to force the prongs of a fastener through the fabric or material and clinch them thereunder, the combination therewith of a button and fastener holder, as *d*, arranged between said jaws and secured to the lower or die-carrying member, two yielding stops mounted on said holder portion, a pin or projection secured to the upper jaw member, arranged in vibrating the jaw to intermittently engage and control the action of the stops, and a removable tube or magazine attached to and communicating with the upper end of said holder, substantially as described.

4. A button-setting instrument having two jointed jaw members arranged to attach buttons to fabric or other suitable material, a holder or runway secured to the lower jaw or die-carrying member, the mouth of the holder being in close proximity to the face of the die and in a fixed relation thereto, and yielding stops actuated and controlled by the movement of the upper jaw, substantially as hereinbefore described, and for the purpose set forth.

5. In a button-setting instrument, the combination, with an anvil member having a button and fastener holder or guide in a fixed or unchanging position or relation to said member, of a pivoted arm or member and a driver secured thereto, arranged to work from the rear of the holder, for the purpose hereinbefore set forth.

In testimony whereof I have affixed my signature in presence of two witnesses.

JAMES F. THAYER.
